(57) **CLAIM**

The ornamental design for an adhesive layered retaining clip, as shown and described.

DESCRIPTION

FIG. 1 is a perspective view of the retaining clip comprising the present invention;

FIG. 2 is a side elevation view thereof, the opposite side elevational view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.
